A. W. HAWKINS

SADDLE

Filed April 8, 1921

Patented July 24, 1923.

1,462,885

UNITED STATES PATENT OFFICE.

ARCHIE W. HAWKINS, OF ST. LOUIS COUNTY, MISSOURI, ASSIGNOR TO SIMMONS HARD-WARE COMPANY, OF ST. LOUIS, MISSOURI, A CORPORATION OF MISSOURI.

SADDLE.

Application filed April 8, 1921. Serial No. 459,687.

To all whom it may concern:

Be it known that I, ARCHIE W. HAWKINS, a citizen of the United States of America, and a resident of the county of St. Louis and 5 State of Missouri, have invented certain new and useful Improvements in Saddles, of which the following is a full, clear, and exact description, reference being had to the accompanying drawings, forming a part of 10 this specification.

This invention relates to improvements in saddles and has for one of its objects the production of a saddle of the so called "cow-boy" style, which, while having the 15 general outward appearance of the said "cow-boy" saddle, may be used with comfort and safety by persons not so accustomed to riding as are the users of this style of saddle.

20 It is a well known fact that horseback riding in hilly or mountainous country, where the trails are very steep, is fraught with much danger if the rider is not accustomed to such riding.

25 The reason for the danger mentioned lies in the fact that the inexperienced rider cannot retain his proper place in the saddle when the front of said saddle is in a lower plane than the rear thereof, the tendency 30 being for him to slide forward in the saddle, and because the stirrup straps cannot be extended forwardly to any great degree, the rider cannot brace himself against this movement, as a result of which he is often 35 unseated.

To overcome the objections set forth above 40 I provide the seat of my saddle with depressions at the point where the body of the rider rests, which render the seat more comfortable and tend to prevent the rider from sliding about in the saddle.

I also provide stirrup straps which are so 45 attached as to be capable of being freely extended in a forward direction, thereby making it possible for the rider to brace himself against the forward sliding movement already mentioned.

With the foregoing and other objects in view, the invention comprises the novel 50 construction, combination and arrangement of parts hereinafter more specifically described and illustrated in the accompanying drawings wherein is shown the preferred embodiment of the invention. However, it 55 is to be understood that the invention com-

prehends changes, variations and modifications which come within the scope of the claims hereunto appended.

Fig. I is a side elevation of my improved saddle, the stirrup straps being shown in a 60 forward position by dotted lines.

Fig. II is a plan of the saddletree.

Fig. III is a side elevation of the saddletree.

In the drawings, A indicates a saddle of 65 the cow-boy type which is provided with a saddletree B, said saddletree having the usual pommel C, horn D and cantle E, and is also provided with the usual side bars G and central opening or cutout portion H. 70

My improved saddle preferably includes a front jockey 1 and a rear jockey 2, each of which is secured to the saddletree by means of strings or thongs 3. The manner of fastening the front and rear jockeys in place 75 consists in passing the free ends of a string or thong through adjacent apertures 4 in the side bars of the saddletree B, and then through an opening in the jockey members, after which said ends of the string or thong 80 are interlaced, thereby securely fastening said jockey members in place.

To eliminate the possibility of the interlaced portions of the thong ends being pulled through the openings in the jockey members, 85 I provide rosettes 5 which are made of double thickness and each of which is provided with a central opening formed therethrough, which is only of such size as to permit the passage of the thong ends in an unlaced condition. It is apparent that after these ends are interlaced it will not be possible to draw them through the restricted openings in the rosettes 5. 90

A seat and jockey 6 is provided with forwardly extending portions 7, adjacent the pommel on each side thereof and provided with fastening strings or thongs 8 similar to the thongs 3 and which pass through apertures 9 in the saddletree B whereby the forward portion of said seat and jockey is secured to the saddletree B. Strings or thongs 10, similar to the thongs 3 and 8, 100 secure the rear portion of the seat and jockey 6 to the saddletree B. 105

Stirrup straps 11 are secured to the saddletree by looping one of said stirrup straps over each of the side bars G and securing said stirrup straps against longitudinal movement by means of fastening devices, 110

such as nails 12 which pass through said straps and into the inner margins of said side bars G.

As a means of providing a more comfortable seat and to eliminate the tendency of an inexperienced rider to slide forward and backward when the angle of the saddle changes, I provide depressions 13 which are formed in the rear end portions of the side bars G of the saddletree adjacent their inner edges. The seat and jockey 6 and the pad 14 may be shaped to conform to the depression 13 in the saddletree G so that the depressions 13 will be present in the saddle seat.

In the use of a saddle constructed as the one herein disclosed, it is apparent that the depressions 13 will reduce to a minimum the tendency of an inexperienced rider to slide forward and backward, as the angle of the saddle changes and because the fastening means 8 which secure the front portion of the seat and jockey are located at a point removed in a forward direction from said stirrup straps, the stirrup straps may be swung to the position shown in dotted lines in Fig. I, thereby permitting the rider to brace himself against the sliding movement mentioned.

I claim:

1. A saddle provided with a saddletree having side bars, each having an abruptly depressed semicircular portion in its top face near the rear of the saddle, and stirrup straps secured to said saddletree at points in front of said depressed portions.

2. A saddle provided with a saddletree having side bars, an abruptly depressed semicircular portion being formed in the rear portion of each of said side bars at its inside margin, said depressed portion being in the top face of the bar, and stirrup straps secured to said saddletree.

3. A saddle provided with a saddletree, stirrup straps attached to said saddletree, a seat and jockey secured to and surmounting said saddletree, a portion of each of said stirrup straps being interposed between said saddletree and said seat and jockey, and securing means whereby the seat and jockey is secured to the saddletree, said securing means

being located at points remote from said stirrup straps to permit said stirrup straps to swing in a forward direction.

4. A saddle provided with a saddletree having a pommel, stirrup straps attached to said saddletree, a seat and jockey secured to and surmounting said saddletree, a portion of each of said stirrup straps being interposed between said saddletree and said seat and jockey, said seat and jockey being provided with forwardly extending portions adjacent said pommel, one of said forwardly extending portions lying on each side of said pommel, securing means whereby the rear portion of said seat and jockey is secured to the saddletree, and securing means whereby the front portion of said seat and jockey is secured to the saddletree, said last mentioned securing means passing through said forwardly extending portions formed on the seat and jockey at points remote from the stirrup straps to permit the upper portions of said stirrup straps to swing forwardly at the saddle.

5. A saddle provided with a saddletree having a pommel and side bars, stirrup straps looped over said side bars of the saddletree and secured to the inner margins thereof, said straps being free to swing from said inner margins, a seat and jockey secured to and surmounting said saddletree, a portion of each stirrup strap being interposed between said saddletree and said seat and jockey, said seat and jockey being provided with forwardly extending tongues adjacent said pommel, one of said forwardly extending tongues lying on each side of said pommel, securing means whereby the rear portion of said seat and jockey is secured to the saddletree, and securing means whereby the front portion of said seat and jockey is secured to the saddletree, said last mentioned securing means passing through said forwardly extending tongues formed on the seat and jockey at points remote from the stirrup straps to permit the upper portions of said stirrup straps to swing forwardly.

In testimony that I claim the foregoing I hereunto affix my signature.

ARCHIE W. HAWKINS.
